UNITED STATES PATENT OFFICE.

DAVID W. EMERICK, OF KILGORE, NEBRASKA.

DRAFT-EQUALIZER.

1,045,010.

Specification of Letters Patent.

Patented Nov. 19, 1912.

Application filed May 25, 1912. Serial No. 699,678.

To all whom it may concern:

Be it known that I, DAVID W. EMERICK, a citizen of the United States, residing at Kilgore, in the county of Cherry and State 5 of Nebraska, have invented certain new and useful Improvements in Draft-Equalizers, of which the following is a specification, reference being had therein to the accompanying drawing.

10 This invention relates to draft equalizers and has special reference to a device of this character arranged for an easy change of a two-horse to a three-horse equalizer.

15 The principal object of the invention is to improve and simplify the general construction of devices of this character.

20 With the above and other objects in view, the invention consists in general of certain novel constructions, combinations and arrangements of parts as will be hereinafter fully described, illustrated in the accompanying drawings, and specifically claimed.

25 In the accompanying drawings, like characters of reference indicate like parts in the several views, and Figure 1 is a plan view of the device partly broken away showing the same in use as a two-horse equalizer. Fig. 2 is a similar view showing the device used as a three-horse equalizer. Fig. 3 is a 30 transverse section through the wagon tongue when the device is in position for use as a three-horse equalizer. Fig. 4 is a detail view of a supporting arm or brace used in connection with the device. Fig. 5 is a detail 35 view of a certain strap used in making connection with the axle of the wagon. Fig. 6 is a plan view of an equalizer bar. Fig. 7 is an edge view thereof.

40 In the present embodiment of the invention there is provided the usual wagon axle 10 whereto is attached a pole or tongue 11 the same being properly braced by braces 12. At a point somewhat in advance of these braces there is provided a laterally 45 projecting arm 13 and this arm is securely fixed to the tongue at its inner end and is provided at the inner end with an opening registering with an opening in the tongue as indicated at 14. Adjacent the outer end 50 of the arm is provided a hook 15 and between the outer and inner end there is a second opening 16. Surrounding the axle 10 is a clip which consists of a strip of metal bent to conform to the shape of the axle 55 and having its bottom part tapered to form a hook. The body of the strip is here indi-

cated at 17 and the hooked end at 18. This strip has its front and rear vertical portions provided with opposed openings 19 wherethrough pass suitable bolts 20 which 60 serve to hold the strip in position. Extending from the hook 18 to the hook 15 is a chain 21 which serves to brace the outer end of the arm 13 and it is to be noted that this chain extends diagonally across the tongue 65 as can be clearly seen by reference to Figs. 1 and 2. The tongue is provided with the usual hammer strap 22 but in the present instance this strap is pivotally mounted on the tongue as at 23 and is provided with an 70 opening 24 adjacent its end and an intermediate opening 25 which, when the strap is swung over the tongue will register with the openings 14.

75 There is furthermore provided an equalizer bar 26 having a centrally disposed opening 27 and a second opening 28. This equalizer bar is provided with hooks 29 adjacent each end and the position of the opening 28 is such that the distance from one of 80 the hooks 29 is twice as great as that from the other hook 29. These hooks are used when the device is in use as a two-horse equalizer for the attachment of swing trees 30, while when the device is used as a three- 85 horse equalizer the hook nearest the opening 28 is used for the attachment of a double tree 31 whereto may be attached the swing tree 32. When in use as a two-horse equalizer a bolt 33 is passed through the openings 90 27, 25, and 14 so that the swing trees 30 will be evenly spaced on both sides of the pole 11.

When in use as a three-horse equalizer the equalizer bar is moved to bring the opening 95 28 in alignment with the opening 16 and the bolt 33 is passed through these openings and through the opening 24 in the end of the hammer strap which is swung over to the position shown in Fig. 2 to permit such action. 100

There has thus been provided a simple and efficient device of the kind described, and for the purpose specified.

Having thus described the invention, what is claimed as new, is;

105 In a draft equalizer, an axle, a pole rigidly attached to said axle and extending forwardly therefrom, said pole being provided with an opening therethrough, an arm extending laterally from the pole having an 110 opening registering with the opening in the pole, a second opening spaced from the pole,

a clip secured to said axle on the side opposite that from which the arm extends, a chain connecting the clip and the outer end of said arm, a hammer strap having its rear end pivotally connected to said pole between the axle and the opening in the pole, said hammer strap being provided with an opening adapted for registration with the opening in the pole, and a second opening adjacent its end adapted for registration with the opening in the arm, an equalizer bar provided with a centrally disposed opening, and a second opening in spaced relation to the centrally-disposed opening, tree attaching

means adjacent the ends of said equalizer bar, the distance between the second opening in the equalizer bar being twice as great from one of said tree-attaching means as from the other thereof, and a bolt adapted to pass through selective one of said openings.

In testimony whereof I hereunto affix my signature in presence of two witnesses.

DAVID W. EMERICK.
